GEORGE T. ROYDEN, OF PALO ALTO, CALIFORNIA, ASSIGNOR TO FEDERAL TELEGRAPH COMPANY, OF SAN FRANCISCO, CALIFORNIA, A CORPORATION OF CALIFORNIA

RADIO COMPASS SYSTEM

Application filed December 28, 1926. Serial No. 157,482.

This invention relates generally to radio signalling receiving systems especially applicable for locating the direction of a signal source.

In radio compass installations, the receiving apparatus usually includes a rotatable loop antenna connected to a cascade amplifier and detector. Connected to the detector there is a translator which may either consist of a telephone receiver or one or more relays for controlling a visual or audible indicating device. Generally the system is operated by rotating the loop until the signal response is of minimum strength, the position of the loop then indicating the direction of the signal source. In case of a translator employing relays, this condition may be indicated by a visual indicator such as a flashing light. While arrangements of this sort give good results, it is possible that an inexperienced operator may obtain a false bearing due to a cessation of signals from causes other than a critical position of the loop. For example, the signals may become weak due to "fading" effects or because of the condition of the signal transmitter.

It is an object of this invention to devise a radio compass system which will prevent errors by providing means by which an observer may be assured of a proper critical position of the loop.

It is a further object of this invention to devise a signalling system which will indicate the nature of a signal being received by one apparatus by the combined effect of that apparatus and another receiving apparatus upon a common translator.

Further objects of this invention will appear from the following description in which I have set forth the preferred embodiment of my invention. It is to be understood that the appended claims are to be accorded a range of electrical and mechanical equivalents consistent with the state of the prior art.

In the central figure of the drawing I have

shown a radio compass system incorporating the principles of this invention. Such a system utilizes a directional radio receiver comprising for example a rotatable loop antenna 10 connected to suitable receiving apparatus such as a radio frequency amplifier 11, detector 12 and audio frequency amplifier 13. The system is preferably made selective by tuning one or more stages of the radio frequency amplifier 11. For purposes of illustration I have indicated a selectively tuned system by showing a radio frequency transformer 14 coupling together the loop antenna 10 and the amplifier 11, this transformer being tuned by means of a variable condenser 16.

Associated with the directive receiving apparatus described above, there is a non-directional receiver which in a typical instance may comprise a radio frequency amplifier 17, detector 18 and audio frequency amplifier 19. The input of radio frequency amplifier 17 is coupled to an antenna 21 which is preferably non-directional, the antenna having a ground connection 22 to a coupling transformer 23. A selectively tunable system is indicated by variable condenser 24 which is preferably mechanically connected with variable condenser 16 through a gang or common manual control.

The translator or indicator device which is adapted to be influenced by both of the receivers, indicates a critical adjustment of loop antenna 10 when both of the receivers are tuned to the same signal. One suitable form of translator utilizes a mirror galvanometer 26 having its armature 27 connected to the output of amplifier 13. A beam of light from a lamp 28 is focused upon the mirror 29 of this galvanometer, and is reflected upon a screen 31. The lamp 28 is energized from a local battery 32 through a circuit controlled by relay 33. The windings of this relay are connected to the amplifier 19 of the non-directional receiver so as to be energized from the

output of the last amplifier stage. The relay 33 is designed so that for the ordinary audible signal frequency, its armature 34 will not flutter but will be held against contact 36. 5 The armature, however, is biased as by means of a spring 37 so that when no signals are being received by the nondirectional receiver, armature 34 breaks the energizing circuit for battery 32. For observing the position of the 10 light beam, the screen 31 is provided with a window 38, and another window 39 may be provided for observing the condition of lamp 28.

When operating the system as described 15 above, both the directional and non-directional receivers are tuned to a certain transmitting station or to a given source of radio signals. This may be accomplished by using telephone receivers in place of the translator, or the two receiving apparatuses may 20 previously be adjusted so that the operator may merely operate the simultaneous control until lamp 28 is lighted. The galvanometer may then be adjusted so that the beam of 25 light striking the mirror 29 will be reflected along path 41 to illuminate the window 38. To secure a bearing indication, the loop is then slowly rotated to a position of minimum 30 signal strength. This is indicated to the observer by darkening of window 38 due to a deflection in the galvanometer which changes the angle of reflection and thus shifts the beam to path 42. By noting that window 39 is illuminated when window 38 is darkened, 35 the operator may be assured that the bearing observation in the mirror is a true indication of a critical position of the loop 10. It is obvious that instead of having a window 38 darken to indicate a critical condition, the 40 galvanometer 26 may be arranged to deflect the beam to normally darken the window and illuminate it when the signal strength in the directional receiver is at a minimum.

It will be apparent that this system is a 45 decided improvement on radio compass systems which utilize a single receiver. The response of the translator which indicates a critical position of the loop is not merely due to the absence of signal energy, but is due to 50 the reception of signal energy in the one receiver when substantially no energy is being received in the directional receiver. Thus the response is more reliable in that it is positive rather than negative. It is obvious that a 55 differentially wound relay, or a system of interlocking relays may be substituted for the galvanometer arrangement.

I claim:

60 1. In a radio signaling system, two receiving apparatus, each having an independent antenna, a light source adapted to be illuminated by reception of signal energy by one apparatus, and means controlled by the other apparatus for affecting light rays from

said source according to received signal energy.

2. In a radio signaling system, two receiving apparatus, each having an independent antenna, a light source adapted to be illuminated by reception of signal energy by one apparatus, and means controlled by the other apparatus for affecting light rays from said source according to the intensity of received signal energy. 7

3. In a radio signaling system, two receiving apparatus each having an independent antenna, indicating means including a lamp adapted to be illuminated by reception of signal energy by one apparatus, and means controlled by received signal energy from the other apparatus for varying the visual indication produced by said lamp. 8

4. In a radio signaling system, two receiving apparatus each having an independent antenna, indicating means including a lamp adapted to be illuminated by reception of signal energy by one apparatus, and means controlled by received signal energy from the other apparatus for variably deflecting light from said lamp. 9

5. In a radio system, a direction finding apparatus including a rotatable directional antenna associated with a radio detector, indicating means controlled by the output of said detector, and means for preventing a false bearing indication comprising a non-directional receiving apparatus including another radio detector, and means correlating said last detector with said indicating means for independently indicating reception of a bearing signal by said non-directional apparatus. 10

6. In a radio system, a direction finding apparatus including a rotatable directional antenna associated with a radio detector, indicating means controlled by the output of said detector, and means for preventing a false bearing indication comprising a non-directional receiving apparatus including another radio detector, and means correlating said last detector with said indicating means for independently indicating reception of a bearing signal by said non-directional apparatus, said last means serving to render said first named indicating means operative in response to reception of the direction signal by said non-directional apparatus. 11

7. In a radio compass, a receiving system having movable absorption structure, the received energy varying with the amplitude of radiant energy and the position of said structure with respect to the wave-front thereof, a second receiving system of the received energy of which varies solely with the amplitude of said radiant energy, an indicator associated with said first system responsive to the received energy thereof for indicating position, and means responsive to the energy 12

of said second system controlling the operativeness of said indicator.

8. In a radio compass, a directional receiving system, an indicator having a deflecting member whose position is determined by the direction of propagation of energy received by said system, a second receiving system, and means responsive to energy received by said second system controlling the ability of 10 said deflecting member to produce an indication.

In testimony whereof, I have hereunto set my hand.

GEORGE T. ROYDEN.
